[57] **CLAIM**

The ornamental design for a screen for a liquid crystal projector, as shown and described.

DESCRIPTION

FIG. 1 is a front elevational view of a screen for a liquid crystal projector showing our new design;

FIG. 2 is a right side elevational view thereof, the left side elevational view being identical to the right side elevational view;

FIG. 3 is a top plan view thereof;

FIG. 4 is a bottom plan view thereof;

FIG. 5 is a rear elevational view thereof;

FIG. 6 is a front, right-side and top perspective view thereof;

FIG. 7 is a perspective view of the screen, which is received in the screen case with the cover open; and,

FIG. 8 is a perspective view of the screen case in a closed condition, in which the screen is received therein.

1 Claim, 4 Drawing Sheets

FIG. 3

FIG. 1

FIG. 2

FIG. 4

FIG. 5

FIG. 6

FIG. 7

FIG. 8
